(57) **CLAIM**

The ornamental design for a device for securing an animal, as shown and described.

DESCRIPTION

FIG. 1 is a bottom, front, and right side view of a device for securing an animal;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof.

The broken line(s) shown in the drawings are for illustrative purposes only and form no part of the claimed design.

The shading lines shown in the drawings represent the approximate three-dimensional contour of the design, and are not intended to indicate surface decoration.

Portions of the device for securing an animal that are not shown in the drawing(s) form no part of the claimed design.
